UNITED STATES PATENT OFFICE.

SETH T. HUTCHINS, OF NORTH ANSON, MAINE.

IMPROVEMENT IN LASTS.

Specification forming part of Letters Patent No. **56,565**, dated July 24, 1866.

To all whom it may concern:

Be it known that I, SETH T. HUTCHINS, of North Anson, in the county of Somerset and State of Maine, have invented a new and useful Improvement in Lasts; and I do hereby declare that the following, taken in connection with the drawings which accompany and form part of this specification, is a description of my invention sufficient to enable those skilled in the art to practice it.

This invention relates to novel means for placing and holding the blocks of lasts in their places, so that they may be easily secured in position and detached therefrom.

Of the drawings illustrating my invention, Figure 1 shows a last in side elevation with my improvement thereon. Fig. 2 shows a section taken on the line *z z*, Fig. 1; and Fig. 3 shows, in elevation, the inner face of one of the spring-catches which I employ.

The body of the last is marked *a*, and the block *b*. These parts of a last are commonly secured by a steady-pin in the block at the toe end, with a tack or nail driven through the block *b* into the body *a* at about the place marked *c* in Fig. 1; but the driving and pulling out of this nail or tack splits the block and soon ruins it for use. Various devices have been employed to take the place of the nail or tack, intended to save the wear of the block, but from their expense and want of simplicity have failed to come into practical use.

In my invention I retain the use of the steady-pin at the toe end of the block, this being shown in dotted lines in Fig. 1, my invention consisting in the combination, with the steady-pin or dowel, of spring-pieces *d*, on both sides of the block, secured thereto and springing over and catching and holding on projections *e* in or on the sides of the body of the last.

The guiding and holding pieces *d* are pref-

erably formed of sheet-steel, though other material may be made to answer. These pieces are best secured to the block by a screw in each piece *d*, at the upper end thereof, as shown in the drawings, the pieces *d* being prevented from turning by the corners, which are bent down at *f f*, forming spurs or points, which are driven into the block. In the lower end of each piece *d* a hole is made and is countersunk from the inner face, so as to fit upon the projections *e* in the last, these being cheaply made by round-headed nails driven therein.

When the block is in place it is easily removed by a pull with the ordinary block-hook inserted in the hole *g*, the inclines or curves on the projections *e* and the inclines of the countersunk holes surrounding these projections causing the pieces *d* to spring under the force of the pull exerted through the hook, and liberating the block from its confinement.

To replace the block the steady-pin or dowel is entered in its hole, and then a push upon the block downward and forward will cause the pieces *d* to spring over the projections *e* and close upon them with a snap.

Immaterial changes in the details of construction—such as using two screws for holding each piece *d*, and dispensing with the spurs *f*, or making projections on the pieces *d* and corresponding countersinks or depressions in the body of the last—are no departure from the spirit of my invention.

I claim—

The self-operating spring-clasps *d* and projections *e*, combined and operating together to hold and to release the last-block, substantially as described.

SETH T. HUTCHINS.
